PRODUCTION OF OXYGENATED TERPENES FROM ALPHA-PINENE

Joseph P. Bain and Wilbur Y. Gary, Jacksonville, Fla.,
assignors to The Glidden Company, Cleveland, Ohio,
a corporation of Ohio

No Drawing. Application April 30, 1953
Serial No. 352,291

11 Claims. (Cl. 260—631.5)

The present invention relates to the production of oxygenated terpenes from alpha-pinene.

Alpha-pinene is a major constituent of turpentine. It is known that it can be oxidized by air or oxygen, and verbenol and verbenone have been identified in the products resulting from the steam distillation of the peroxides formed by the oxidation. Selenium dioxide oxidation of alpha-pinene yields myrtenol and myrtenal. It has also been reported that in the presence of air, water and sunlight, alpha-pinene yields sobrerol, Beilstein, 6; 752. Also, alpha-pinene oxide has been formed by the oxidation of alpha-pinene with perbenzoic acid.

Oxidation by air or gaseous oxygen is an economically desirable means of oxidation, but the steam decomposition of the oxidation mixture leaves much to be desired. It causes formation of substantial quantities of undesirable products and produces low yields of some of the desirable products.

It is accordingly an object of the present invention to provide an improved process for producing oxygenated products from alpha-pinene.

Another object is to provide an improved process for treating the mixture resulting from the air-oxidation of alpha-pinene.

A further object is to produce certain hitherto unknown alcohols.

An additional object is to provide a new method for the production of verbenol, verbenone and alpha-pinene oxide.

Still another object is to provide a process for produc-

ing a mixture of alpha-pinene oxidation products substantially free of secondary by-products which render difficult the separation and purification of the pinene oxidation products.

Still a further object is to provide a process for producing optically active oxygenated terpenes.

Still another object is to provide an improved process for producing alpha-pinene oxide.

Other objects will be apparent to those skilled in the art from the following description of the invention.

It has been found that the foregoing objects can be accomplished when the air oxidation mixture is treated with a reducing agent under non-acidic and preferably alkaline conditions. When treated in the preferred manner, the reaction mixture can be fractionally distilled to produce alpha-pinene oxide, verbenol, verbenone and both the cis- and trans-forms of the hitherto unknown alcohol, 3-pinene-2-ol. In addition to the afore-mentioned products, myrtenol and myrtenal can also be isolated.

As indicated, alkaline conditions are preferred for the decomposition of the initial oxidation products. When excess sodium sulfite is employed, the reaction mixture should tend to remain alkaline due to hydrolysis of this salt of a weak acid. As the sulfite is consumed, the alkalinity induced by hydrolysis decreases so that alkalinity is maintained only if excess sulfite is present. Thus, in the absence of sulfite the pH decreases, thus permitting, for example, hydration of pinene oxide, which is attacked by distilled water. Further, while perhaps water of pH 7.5 when cold will not attack the oxide appreciably, that same water when hot would attack it. Further, if the sulfite employed were slightly acidic, it would become much more acidic on being oxidized. To avoid these undesirable possibilities, we prefer to add excess alkali, such as soda ash, caustic soda, etc. in small amount, suitably corresponding to 1 to 3% concentration in the aqueous phase. This alkali furthermore would neutralize any acidity present in the peroxidized pinene under treatment. By use of such a cheap safeguard, it is unnecessary to provide excess sulfite over that required for reduction and whose only purpose would be to maintain suitable alkalinity. Thus, while nonacidity is necessary to our invention, alkalinity is preferred.

The reactions may be represented as follows:

The yields of the various products vary somewhat, depending upon the conditions, but representative yields obtained are as follows, based on oxygenated products:

Compound	$b_{10\text{ mm.}}, ^\circ\text{C.}$	Percent yield by weight
α -pinene oxide	69	22.5
trans-3-pinene-2-ol	76	1.0
cis-3-pinene-2-ol	83	15.5
myrtenal	91	1.3
verbenol	96	29.6
verbenone	97	6.3
myrtenol	102	4.6
residue		17.9

It is to be noted that the pinane structure was retained in the products. Thus, when optically active α -pinene is used, the products are optically active.

The oxidation can be carried out over any suitable temperature range. At lower temperatures, the reaction may be quite slow, while at temperatures of 80-90° C., there is some decomposition of the oxidation products. We prefer temperatures between 40-60° C., and particularly about 50° C. ($\pm 5^\circ$). The duration of the oxidation will vary according to the temperature, oxygen concentration in the oxidizing gas and the particular degree of oxidation desired. Preferably the oxidation is continued to a peroxide value between about 1000 and about 2000 and the mixture then reduced, since at peroxide values below about 1000 the quantity of pinene per unit of oxidation product to be recovered and reused becomes burdensome, whereas peroxide values of over 2000 are more difficult to obtain economically and without encountering undesirable by-products among the recovered oxidation products. A pure terpene hydroperoxide has a theoretical peroxide value of about 12,000 as defined by Wheeler; Oil and Soap, 9, 89 (1932), so that an air-oxidized α -pinene of peroxide value of 1500 would contain about 12.5% peroxides.

The peroxidized pinene and reducing agent are reacted until a low peroxide value is reacted, and after separation of the reduced organic layer, distillation and crystallization follow to recover unattacked pinene and the individual oxygenated derivatives.

Any reducing agent capable of absorbing oxygen from the air can be used. We have found sodium sulfite to be quite suitable, but other reducing agents, such as sodium sulfide, ferrous hydroxide, alkaline pyrogallol, pyroligneous acid made alkaline, etc. can be used. Any suitable temperatures can be used, preferably not much above 80-90° C., since if the reduction is carried out with an aqueous system at atmospheric pressure, unnecessary distillation or reflux would occur at somewhat higher temperatures than these, and further, any pinene oxide that would be so volatilized would react with the water condensate unless the vapor and vapor condensate were kept sufficiently alkaline, as by means of a suitable volatile base such as ammonia or an amine which might be incorporated in the reduction system. Whether any heat need be applied at the reduction step depends on the rate of reaction desired and on the identity of the reducing agent, whether an aqueous reducing system substantially totally immiscible with the peroxidized pinene is employed and if such a system is employed then upon the degree of agitation employed and whether emulsifiers are present or not. Cooling the reduction system below ambient temperatures would be expensive and we have not found it necessary or desirable to perform the reductions at lower than ambient temperatures.

Good quality commercial α -pinenes are suitable as raw materials. If oxidation products of high optical activity or of a specific optical sign are desired, the α -pinene used as raw material should be chosen accordingly. Both dextro-pinene and levo-pinene were oxidized and the oxidation products converted by our methods. Levo- α -pinene of optical rotation, $\alpha_D^{25} -36.8^\circ$ (10

cm. tube) was produced by isomerization of very pure β -pinene. This pinene contained about 3% camphene which did not air oxidize and therefore increased in concentration in the recovered pinene recycled to a new oxidation. The α -pinene employed need not be of highest purity but such impurities as β -pinene and limonene, for example, will themselves oxidize and such oxidation products will accompany the α -pinene oxidation products in the recovery operation thereby rendering more difficult purification of some of the α -pinene oxidation products. The α -pinene does not require any special pretreatment as, for example, special dehydration beyond that practiced in commercial pinene manufacture. Where air is passed through the pinene, it will, if dry, remove moisture from the pinene. Pinene condensed from such an air stream passing through warm pinene may tend to be wet and free water may be removed by decantation before returning such condensed pinene to the oxidation equipment.

The following examples are illustrative, wherein all temperatures are in degrees centigrade and extinction coefficients for compounds possessing an absorption maximum in the ultraviolet are expressed as the specific extinction coefficient

$$\alpha = E_{1\text{ cm.}}^{\text{g./l.}}$$

EXAMPLE 1

Air was passed through α -pinene by means of an air distributor as the pinene was maintained at about 50 $\pm 5^\circ$ until the peroxide number rose to about 1000 to 1600. About 100 to 140 hours were required to attain this degree of oxidation when starting the oxidation from zero peroxide value. It was found, however, that gain in peroxide value accelerated throughout the run, and therefore it was convenient in processing large quantities of pinene to withdraw continuously or periodically part of the material as it reached a peroxide value of 1200 to 1600 and replace it with fresh pinene, so that the peroxide value did not fall below about 600 or exceed about 1600. The exit air-pinene vapor mixture was passed through an efficient condenser arranged so that condensed pinene was returned to the oxidation mixture and the air saturated with pinene vapor discharged to the atmosphere was at about 30°. The weight of peroxidized pinene was about equivalent to that of the starting pinene. Air was not measured carefully, but the oxidation was considered to be proceeding satisfactorily when measurements showed that 15 to 30% of the oxygen available was being fixed by the pinene. Only traces of acids were formed on oxidation, generally less than 0.5% calculated as acetic acid. In order to avoid the possibility of acid affecting the course of the reaction or reacting with the oxidation products, about 1% sodium carbonate was added prior to air blowing in some experiments, but the effect was usually not marked unless the starting pinene was itself slightly acidic.

The peroxidized pinene was reduced by agitation with an excess of concentrated aqueous sodium sulfite solution at about 80 to 90°. The time required to decrease the peroxide value to about 10 was about two hours. The reduced product was then fractionated at about 100 mm. pressure to remove unreacted pinene, now somewhat richer in camphene which was present in the commercial pinene in amounts of the order of 1 or 2% and which did not oxidize appreciably. This unreacted crude pinene amounted to 70 to 80% of the charge when the pinene had been oxidized to a peroxide value of about 1200, and was of quality suitable for further oxidation. The pressure was then reduced to 10 mm. and the fractionation of the oxygenated products was begun, employing columns of 40 to 75 plates at reflux ratios which were varied from about 10:1 to 30:1 as required to provide a fair degree of separation of products. About 80 to 90% of the oxygenated products were volatile under

these conditions, and boiled over the range 65 to 110°. Fractions were regrouped according to composition as determined by analysis by infrared methods, and further purification was accomplished by refluxation, or where applicable, crystallization was employed. The purity of all products reported here is estimated to exceed 98%, as judged by infrared data on consecutive samples from efficient fractionation and crystallizations.

(A) Pinene oxide (VII) boiled at 69° at 10 mm., d_4^{25} 0.960, N_D^{25} 1.4668, and was readily purified by fractionation. When produced from *l*- α -pinene, α_D^{25} -36.8° (10 cm. tube), the pinene oxide showed $[\alpha]_D^{25}$ -106°, and when produced from pinene of α_D^{25} +19.6° (10 cm. tube), the pinene oxide showed $[\alpha]_D^{25}$ +57°. These data are in good agreement with those of Prilezhaev, J. Russ. Phys. Soc. 61, 445-65 (1929), who first produced the product by perbenzoic acid oxidation of pinene and who reported B.P. 103-104° at 50 mm., d_{15}^{15} 0.9675, N_D^{15} 1.4715, and $[\alpha]_D$ -97.8°. The pinene oxide was further identified by hydration to sobrerol.

(B) Trans-3-pinene-2-ol (VIIIa). Fractions containing some trans- but mainly cis-3-pinene-2-ol were cooled and centrifuged to remove most of the cis-form, and the resulting mother liquor was refluxated to obtain fairly pure trans- material which was further purified by partial freezing and centrifuging. It was isolated in pure form only from the oxidation of *l*- α -pinene, B.P. 76° at 10 mm., freezing point 44° $[\alpha]_D^{27}$ +24.4° (36% in heptane), N_D^{55} 1.4730, d_4^{55} 0.9429.

Upon hydrogenation over platinum oxide at 30-60 pounds pressure, the theoretical quantity of hydrogen was absorbed corresponding to one double bond. The hydrogenated product after recrystallization from hexane showed $[\alpha]_D^{25}$ -5.84° (18.2% in ether), and freezing point 57°. A concentrated benzene solution of the hydrogenated product shaken with 35% sulfuric acid at about 30° for seven hours deposited crystals of cis-terpin hydrate, M.P. 116-117°. These properties are in good agreement with those reported by Wallach, Ann., 356, 239 (1907), for the pinane-2-ol obtained by reaction of nopinone with methyl magnesium iodide.

Upon shaking 10 grams of the trans-tertiary alcohol with 20 ml. of 2.5% sulfuric acid at 50° for 30 minutes, the resulting product was found to contain 70% verbenol of the same configuration as obtained in this work by direct oxidation of pinene, and no unreacted tertiary alcohol remained.

Since this lower boiling 3-pinene-2-ol possesses a lower refractive index and density than the higher boiling form, it has been assigned the trans-configuration, and the cis-configuration is assigned to the higher boiling isomer.

(C) Cis-3-pinene-2-ol was purified by fractionation, partial freezing of the richest fractions, and centrifuging. The purified product boiled at 83° at 10 mm., d_4^{55} 0.9477, N_D^{55} 1.4776, freezing point 46°, cap. M.P. 48-49° C. From *l*-pinene oxidation the product showed $[\alpha]_D^{25}$ +130.1° (2.7 grams diluted to 10 ml. with heptane).

The optically pure forms of this alcohol are less soluble than the racemic form, and therefore it was possible to isolate the levo form by repeated crystallization of the partly racemic alcohol produced by oxidation of *d*- α -pinene of α_D^{25} +19.6° (10 cm. tube). The thus purified levo form showed $[\alpha]_D^{25}$ -132.0° (2.47 grams diluted to 10 ml. with heptane).

Equal parts of dextro- and levo- forms were mixed to produce a sample of the racemic product, freezing point 20°, M.P. 19.5-20.5°.

Upon hydrogenation of the levo-form, one mole of hydrogen was absorbed, and the product, after recrystallization from hexane, melted at 76-77°, $[\alpha]_D^{25}$ -24.7° (3.8 grams diluted to 10 ml. with methanol). Hydration of this product with 35% sulfuric acid yielded cis-terpin hydrate, M.P. 116-117°. These data are in good agreement with those of Lipp, Ber., 56 2098 (1923), for the

pinane-2-ol produced by permanganate oxidation of pinane.

When *d*-cis-3-pinane-2-ol was stirred with an equal volume of 1% sulfuric acid for 1 minute, the temperature rose to 50° and infrared analysis showed the product to be 86% verbenol of the same configuration as that obtained in the course of this work by air oxidation of pinene. On fractionation, the best cuts as judged by infrared analysis boiled at 95.5° at 10 mm. and showed N_D^{25} 1.4898, $\alpha_D^{27.5}$ -162.8° (10 cm. tube), $[\alpha]_D^{27.5}$ -169.0°. Simonsen gives -168.75°. Melting point was 22.5°.

Oxidation of *l*-cis-3-pinene-2-ol (from *d*-pinene) with Beckman's chromic acid mixture produced an 80% yield of verbenone $[\alpha]_D^{25}$ +269°, the highest optical rotation for this compound encountered in the course of this work.

(D) Myrtenal (V) from *l*-pinene was isolated by repeated fractionation, having B.P. 91° at 10 mm., $[\alpha]_D^{25}$ -14.3°, N_D^{25} 1.5010, $d_4^{27.2}$ 0.9812. The extinction coefficient, α , of the purest sample was 65.5 at its wavelength of maximum absorption, $\lambda_{\max}$ 240 m μ in iso-octane. Further identification was made by conversion to the semi-carbazone, M.P. 224°.

(E) Verbenol (III). The product isolated from the *l*- α -pinene boiled at 96° at 10 mm., N_D^{25} 1.4889, $[\alpha]_D^{25}$ -151 (10 cm. tube). It was separated from small quantities of accompanying verbenone by partial crystallization and centrifuging, and then showed M.P. 22°, d_4^{25} 0.965, N_D^{25} 1.4894, α_D^{25} -157° (10 cm. tube), data in fair agreement with those recorded for trans- verbenol. There was no evidence of the presence of cis- verbenol among the oxidation products.

(F) Verbenone (II) could not be isolated by fractionation from the verbenol or myrtenol-rich fractions in a state of purity. Oxidation of mixed verbenol- verbenone fractions from *l*- α -pinene with Beckman's chromic acid yielded pure verbenone, B.P. 97° at 10 mm., N_D^{25} 1.4935, M.P. 10.2°, d_4^{25} 0.971, α_D^{25} -246.4° (10 cm. tube). The extinction coefficient, α , was 51.6 at the wavelength of maximum absorption, $\lambda_{\max}$ 240 m μ .

When prepared in the same manner from α -pinene, α_D^{25} +19.6° (10 cm. tube), verbenone showed M.P. 1°, α_D^{25} +129° (10 cm. tube).

(G) Myrtenol (IV) was isolated as crude verbenone- myrtenol fractions, from which myrtenol could not be isolated satisfactorily by repeated fractionation or by extraction of verbenone by sodium bisulfite. It was found, however, that such fractions could be first esterified with a slight excess of acetic anhydride, and then fractionated to yield pure verbenone and pure myrtenyl acetate. The myrtenyl acetate derived from *l*-pinene boiled at 105-106° at 10 mm. and possessed d_4^{31} 0.9810, N_D^{25} 1.4700, α_D^{25} -46° (10 cm. tube). Saponification of the acetate yielded pure myrtenol, B.P. 102° at 10 mm., $d_4^{27.6}$ 0.974, N_D^{25} 1.4942, α_D^{25} -48.7° (10 cm. tube). These data are in good agreement with those of Schmidt, C.A., 37 4716 (1943) for *l*-myrtenol prepared by oxidation of *l*- α -pinene.

(H) Verbenene (VI). Refractionation of crude verbenol derived from the *l*- α -pinene yielded a low-boiling fraction on several occasions. Refractionation of this material yielded pure verbenene, B.P. 92° at 100 mm., 42° at 10 mm., N_D^{25} 1.4975, d_4^{25} 0.881, α_D^{25} +84.4° (10 cm. tube). These data are in good agreement with those reported by Blumann and Zeitschel, Ber., 54, 887 (1921), for verbenene produced by dehydration of verbenol.

Verbenene was also produced by dehydration of pure verbenol with acids, and the product showed the same physical properties, including ultraviolet and infrared absorption spectra. These facts, plus the fact that it could not be detected in the mixture resulting from the reduction step, indicate that the verbenene was formed during the distillation.

Partial hydrogenation of verbenene at 25 to 50 pounds per square inch pressure and room temperature with a

platinum oxide catalyst yielded a mixture of 26% α -pinene and 50% β -pinene.

In Table I are given sufficient of the characteristic absorption bands in the infrared region for the various products to provide identification.

Table I

Infrared absorption bands characteristic of pinene derivatives expressed as frequency in reciprocal centimeters:

Trans- <i>verbenol</i> :	726, 772, 823, 853, 898, 926, 933, 998, 1026, 1139.	10
Myrtenal:	699, 780, 801, 889, 910, 966, 1043, 1129, 1170, 1613, 1673.	
Pinene oxide:	698, 767, 819, 841, 849, 964, 1094, 1269.	
Cis-3-pinene-2-ol:	736, 755, 856, 903, 1021, 1085, 1109, 1166, 1250.	15
Trans-3-pinene-2-ol:	731, 757, 856, 905, 921, 1007, 1040, 1120, 1250.	
Verbenone:	744, 761, 820, 863, 975, 1036, 1079, 1205, 1242, 1285, 1615, 1670.	
Myrtenol:	774, 803, 887, 986, 1013, 1057, 1208, 1650.	

EXAMPLE 2

α -Pinene was air oxidized substantially as described in Example 1 to a peroxide value of 1500. A 4300 cc. aliquot of the air oxidation mixture was stirred with 2 liters of saturated sodium sulfite solution, warmed slowly to 85° C. and held there for 2 hours and 35 minutes, at which time the peroxide value was 62. The reaction was stopped at this point and the oil layer, weighing 3753 grams, was then fractionated. The bulk of the unreacted α -pinene was removed at 100 mm. absolute pressure, after which most of the oxygenated products were fractionated at 10 mm. Near the end of the distillation the pressure was reduced to 1-2 mm. to remove the last of the oxygenated products. The analytical results obtained from examination of the products resulting from the treatment are shown in Table II.

EXAMPLE 3

Another 4300 cc. aliquot of the air oxidation mixture produced in Example 2 was stirred and heated to a maximum temperature of 85° C. with two liters of saturated aqueous sodium sulfite plus 20 grams of sodium hydroxide. In 2½ hours the peroxide value was down to 25 and the reaction was stopped. The oil phase, 3795 grams, was worked up as in Example 2 and the products analyzed. The results are shown in Table II.

Table II

[Oxygenated products recovered as percent of oxygenated distillate. Shown in parenthesis ( ) are percent of product recovered based on weight of crude air oxidized pinene of peroxide value about 1600.]

Oxidation product	Example 2	Example 3
α -Pinene-oxide	15.4 (3.23)	26.2 (6.11)
3-Pinene-2-ols	12.1 (2.54)	25.0 (5.84)
Verbenol	21.8 (4.58)	31.4 (7.34)
Verbenone	12.1 (2.54)	8.0 (1.87)
Pinocarveol	4.1 (0.86)	
α -Campholenaldehyde	3.3 (0.69)	
Myrtenol		5.4 (1.26)
Myrtenal	0.2 (0.04)	
Carveol	3.3 (0.69)	
Not identified	27.7 (5.91)	4.0 (0.91)
Distillation residue		(8.75) (2.64)
Recovered α -pinene	(69.00)	(68.00)
Total	100.0 (98.83)	100.0 (93.97)

The difference between 100% and the total recorded in parentheses ( ) represents loss of product in decomposing the peroxidized pinene and is due to handling loss, loss of product to the aqueous phase, etc.

EXAMPLE 4

5000 cc. of air oxidized α -pinene, peroxide number 1230, was stirred together with 5000 cc. of pyroligneous acid made alkaline with sodium hydroxide. The temperature of the mixture rose to 71° C. without external heat. The mixture was then warmed to 90° C. for 2 hours with

stirring, by which treatment the peroxide number was reduced to 14 with concurrent oxidation of the pyroligneous acid. The oil layer was separated and amounted to 4908 cc. 4865 cc. of this reduced product was stripped of its pinene content to yield 764 grams of oxygenated products boiling above pinene. On fractionation of this material, there was obtained 631 grams of distillate fractions, 100 grams residue and 33 grams loss. The oxygenated distillate showed on analysis of the fractions by infrared spectrophotometry:

	Percent
α -Pinene oxide	25.4
3-pinene-2-ol	25.9
Verbenol	37.3
Other compounds, including verbenone, myrtenol and myrtenal	11.3

Referred to the original air oxidized pinene, this becomes:

	Percent
α -Pinene oxide	3.72
3-pinene-2-ol	3.80
Verbenol	5.49
Verbenone	Trace
Minor Compounds	1.65
Residue	2.45

EXAMPLE 5

Twenty-two hundred and forty milliliters of α -pinene which had been oxidized to a peroxide number of 1600 was added to a stirred ferrous hydroxide slurry produced by mixing a solution of 707 grams $\text{FeSO}_4 \cdot 7\text{H}_2\text{O}$ in 2 liters of water with 283 grams NaOH in 849 grams water. Upon adding the peroxidized turpentine to the dirty greenish reducing mixture a color change to brown-red began immediately and the temperature of the mass rose to 55° C. in a short time. The slurry became somewhat stiffer as the ferrous hydroxide was converted to ferric hydroxide. At the end of an hour and a half of stirring, the slightly exothermic reduction was about over and the temperature had decreased to 50° C. After standing overnight, the thick slurry was centrifuged and filtered to remove the solid ferric hydroxide and the oil layer of the filtrate which now had a peroxide value of only 9 was fractionated at 100 mm. pressure at a low reflux ratio to recover high quality unchanged pinene. When the bulk of the pinene had been recovered, the reflux ratio was increased and the absolute pressure was decreased to 10 mm. for further distillation to recover fractions enriched in the pinene oxidation products. Analysis by infrared methods of the fractions which together with the residue weighed 441 grams showed that the products boiling above pinene consisted of:

	Percent
Pinene oxide	21.4
3-pinene-2-ol	123.1
Myrtenal	2.1
Verbenol	25.3
Verbenone	7.8
Myrtenol	4.1
Still residue	13.8
Undetermined	2.4
Total	100.0

¹ Total of the two forms.

While the foregoing examples show the use of air as the oxidizing medium, any oxygen-containing gas, including pure oxygen, can be used to produce the oxidation mixture. Preferably, good contact between the oxidizing gas and the pinene is maintained and this may be provided by the use of gas distributor devices, by counter current flow, or other means.

The examples also all show alkaline conditions, and

this is a preferred condition. However, in some experiments, only about the calculated amount of sulfite was employed to accomplish reduction and in these cases, optimum results were not obtained. Apparently, one reason for this was because the pH of the aqueous phase decreased sufficiently during the conversion of sulfite to sulfate that the most sensitive components of the oxidation mass, such as pinene oxide, were attacked by the water. This undesirable result was not encountered when sulfite was present in great excess or where a small amount of free alkali was present throughout the reduction step. Thus, in the broadest concept of the invention, neutral conditions are contemplated for the reduction. There are definite advantages in maintaining alkaline conditions throughout the course of the reduction.

In general, it has not been found particularly advantageous to concentrate the peroxides by separation of pinene from peroxidized pinene prior to reduction of the peroxides. If such separation of pinene from peroxides and other oxygenated components of the initial oxidation mixture prior to reduction is desired, this result can be accomplished by employing such methods as stripping off the pinene, or part of it, at low temperatures and pressures in vacuo. Alternatively, the peroxidized pinene may be contacted with a solvent substantially immiscible with pinene but miscible with pinene oxidation products. Such a selective solvent is methanol, preferably containing a few percent water. Other suitable polar extraction solvents include ethanol, isopropanol, dioxane, acetone and mixtures of these, propylene glycol, etc., which may suitably contain some water or not depending on the exact nature of the selective extraction desired.

The examples contain certain illustrations of purification of products by chemical means. It will, of course, be obvious to those skilled in the art that other means than those specifically mentioned can be employed for purification and/or separation of the various products. Thus, alcohol-carbonyl containing mixtures can be purified as to one or more of the constituents by treatment with reagents for the carbonyl group, such as hydroxylamine, semicarbazide, phenylcarbazide, Girard's reagent, methyl alcohol, glycols, etc., and the reaction products then separated from unreacted material. Similarly, in addition to esterification, reagents for alcohol groups, such as boric acid, can be employed to effect either initial separations or purification of enriched fractions. The relative simplicity of the reduction mixture, as compared to those produced by the prior art, makes these methods feasible, the particular choice depending upon the circumstances and the possible value of the reaction products themselves.

As shown by the foregoing, the process of the present invention results in substantially increased yields of volatile oxygenated products which are readily recovered by distillation and crystallization. There is a minimum formation of undesirable secondary products, such as pinocamphone, pinocarveol, pinocarvone, carveol and α -campholene aldehyde. Thus when another aliquot of the oxidation mixture used in Examples 2 and 3 was decomposed by steam, the total percent by weight of pinocarveol, α -campholene aldehyde and carvone, based on the oxygenated distillate was 25.2%, as compared to the 10.7% of Example 2.

The process also results in the production of both the cis- and trans-forms of 3-pinene-2-ol, which has not heretofore been described. This alcohol can be easily isomerized to verbenol in substantial yields. Verbenone can also be converted to verbenol. Since verbenol is also produced directly by the process in substantial quantities, high yields of verbenol are obtainable from the oxidation products. Verbenol has been found to possess disinfectant properties. Thus, an emulsion of 80% of verbenol with 20% of green soap, 50% solids, was found when tested by the method of U.S.D.A. Cir. 198 (1931), when employed with *Salmonella typhosa* at 20° C., to

possess a phenol coefficient of 5.5. This is comparable to the results produced when steam distilled pine oil is converted to a similar composition.

It is also to be noted that there is a substantial yield 5 of pinene oxide produced, which product was not previously found among those produced when steam distillation was employed to decompose the peroxides formed during the oxidation. Pinene oxide can be hydrated to sobrerol, and this then converted to carvone, which can 10 in turn be converted to carveol by known procedures. While steam decomposition of the peroxides produces some sobrerol, the reaction is not easily controlled, and it is distinctly advantageous to treat the pinene-oxide under conditions specifically designed for the particular 15 reaction desired. Moreover, steam decomposition of the oxidation products results in high yields of resinous materials and relatively small yields of volatile products.

The process of the present invention also enables one 20 to produce optically active materials, and in the case of the 3-pinene-2-ols to produce optically pure material, since in such a mixture the optically pure forms are less soluble than the racemic form.

As indicated, any reducing agent for peroxides can be 25 used, provided the reduction is carried out under non-acidic, preferably alkaline, conditions. The temperature of the reduction is not critical and temperatures from 30 to 100° C. have been found suitable. It will, of course, be appreciated that temperatures sufficiently high to cause appreciable pyrolysis of components of the mixture should 30 be avoided for best yields and recovery of unreacted pinene.

The acid isomerization of the 3-pinene-2-ols described herein is more fully described and claimed in the copending application of Bain et al., Serial No. 368,210, filed July 35 15, 1953, now Patent No. 2,818,435, and the oxidation of the 3-pinene-2-ols to verbenone is more fully described in our copending application Serial No. 352,292, filed April 30, 1953, now Patent No. 2,767,215.

Having described the invention, what is claimed is:

40 1. The process for producing 3-pinene-2-ol and pinene oxide which comprises oxidizing α -pinene with gaseous oxygen under substantially anhydrous conditions to produce a mixture of oxidation products containing hydroperoxides and pinene oxide and decomposing the hydroperoxides in said mixture by treating the mixture of oxidation products with a reducing agent for peroxides under aqueous alkaline conditions, the amount of alkaline material being sufficient to maintain the alkaline condition throughout the reduction treatment, whereby there is produced a mixture containing 3-pinene-2-ol and pinene oxide.

45 2. The process for producing 3-pinene-2-ol and pinene oxide which comprises oxidizing α -pinene with gaseous oxygen under substantially anhydrous conditions to produce a mixture of oxidation products containing hydroperoxides and pinene oxide, decomposing the hydroperoxides in said mixture by treating the mixture of oxidation products with a reducing agent for hydroperoxides under aqueous alkaline conditions, the amount of alkaline material being sufficient to maintain the alkaline condition throughout the reduction treatment, whereby there is produced a mixture containing 3-pinene-2-ol and pinene oxide, and fractionally distilling the reduction mixture to recover oxygenated products therefrom.

50 3. The process for producing 3-pinene-2-ol and pinene oxide which comprises oxidizing α -pinene with gaseous oxygen under substantially anhydrous conditions to produce a mixture of oxidation products containing hydroperoxides and pinene oxide, decomposing the hydroperoxides in said mixture by treating the mixture of oxidation products with a reducing agent for hydroperoxides under aqueous alkaline conditions, the amount of alkaline material being sufficient to maintain the alkaline condition throughout the reduction treatment, whereby there is produced a mixture containing 3-pinene-2-ol and pinene

oxide, and recovering 3-pinene-2-ol by fractional distillation of the reduction mixture.

4. The process for producing 3-pinene-2-ol and pinene oxide which comprises oxidizing α -pinene with gaseous oxygen under substantially anhydrous conditions to produce a mixture of oxidation products containing hydroperoxides and pinene oxide, decomposing the hydroperoxides in said mixture by treating the mixture of oxidation products with a reducing agent for hydroperoxides under aqueous alkaline conditions, the amount of alkaline material being sufficient to maintain the alkaline condition throughout the reduction treatment, whereby there is produced a mixture containing 3-pinene-2-ol and pinene oxide, and recovering pinene oxide by fractional distillation of the reduction mixture.

5. The process for producing 3-pinene-2-ol and pinene oxide which comprises oxidizing α -pinene with gaseous oxygen under substantially anhydrous conditions to produce a mixture of oxidation products containing hydroperoxides and pinene oxide, decomposing the hydroperoxides in said mixture by treating the mixture of oxidation products with a reducing agent for hydroperoxides under aqueous alkaline conditions, the amount of alkaline material being sufficient to maintain the alkaline condition throughout the reduction treatment, whereby there is produced a mixture containing 3-pinene-2-ol and pinene oxide, and recovering the 3-pinene-2-ol and pinene oxide by fractional distillation of the reduction mixture.

6. The process for producing 3-pinene-2-ol and pinene oxide which comprises oxidizing α -pinene with gaseous oxygen under substantially anhydrous conditions to produce a mixture of oxidation products containing hydroperoxides and pinene oxide, decomposing the hydroperoxides in said mixture by treating the mixture of oxidation products with a reducing agent for hydroperoxides under aqueous alkaline conditions, the amount of alkaline material being sufficient to maintain the alkaline condition throughout the reduction treatment, whereby there is produced a mixture containing 3-pinene-2-ol and pinene oxide, and recovering from the reduction mixture frac-

tions of successively increasing boiling point enriched in pinene oxide, trans-3-pinene-2-ol, cis-3-pinene-2-ol, myrtenal, verbenol, verbenone and myrtenol, respectively.

7. The process of claim 2 in which a fraction enriched in verbenol is recovered.

8. The process of claim 7 in which a recovered fraction enriched in verbenol but containing some verbenone is subjected to partial crystallization and separation of the crystallized material from the mother liquor.

9. The process of claim 2 in which a fraction enriched in verbenone is recovered.

10. The process of claim 2 in which the α -pinene is optically active.

11. The process of claim 1 in which the oxidation is carried to a peroxide value of between about 1000 and about 2000.
